AUTHER H. DAVIS, OF LONG BEACH, CALIFORNIA.

DRAW-WORKS BRAKE MECHANISM.

Application filed April 23, 1923 Serial No. 634,019.

This invention relates to hoisting drums employing a double band brake, and is more particularly applicable to the draw works of a well drilling outfit. The invention is 5 herein described and illustrated as embodied in a rotary drilling outfit.

In rotary drilling, pipe is let down into the hole by means of the draw works. After withdrawal of the drill pipe for access to 10 the drill, the pipe must then again be lowered. In the case of holes which are deep, the weight of the pipe on the line causes a heavy strain upon the drum. The brakes become exceedingly hot, and, if too much 15 of the work of braking is taken by one of the bands, serious trouble is encountered which may result in causing an explosion of the drum resulting in material damage to the outfit and tools as well as injury to the 20 workers. The primary object of this invention is to provide a construction to equally distribute the braking between the two brake bands and their drums. Another object of 25 this invention is to provide a structure of the character just described which may be applied to the ordinary draw works so that in case of breakage the usual anchors will hold the brake bands.

These objects together with other objects 30 and corresponding accomplishments are obtained by means of the embodiment of my invention illustrated in the accompanying drawing, in which:

Fig. 1 is a perspective view of a draw 35 works including my improved structure; and Fig. 2 is a perspective view on an enlarged scale of my improved structure detached from the draw works.

Referring more particularly to the drawing, 40 3 indicates posts forming a part of the derrick, and mounted thereon are boxes 4 in which is journaled the shaft 5. The usual gears and clutches may be mounted upon the shaft, but as they form no part 45 of the present invention they are not described in detail or illustrated. Fixed to the shaft is the hoisting drum 6 upon which a line is adapted to be wound. At the ends 50 of the hoisting drum are brake drums 7.

Secured to the derrick floor are rods or 55 bolts 8. These rods are arranged in pairs, and mounted upon each pair so as to be adjustable are pins 9. The ends of the brake bands 10 are secured to pins 9. This is the usual construction, and the pins are held in

position by nuts 11 mounted above and below the boxes on the pins. The brake bands are passed around the drums and their other ends are secured to cranks 12 formed in a lever shaft 14, which is journaled in boxes 60 secured to the derrick floor. The lever shaft has a hand lever 15, the lever, shafts, and cranks being preferably formed integral. It is obvious that the lever 15 may be swung so as to tighten the brake bands. The structure just described is the usual draw works construction.

Firmly secured to the derrick floor by any suitable means is a bar 16. Pivotally secured at 20 to the end of bar 16 is a cross-bar 17. At opposite ends of the cross-bar 17 are attachment bars 18 which are pivotally secured to the cross-bar. The brake bands 10 are provided with holes just above the pins 9, and the attachment plates are 75 secured thereto by means of bolts 19. The top nuts 11 of the anchor rods are loosened so that the equalizing anchor will not take the pull upon the brake bands.

It is obvious that the pull upon the brake 80 bands will be equally divided through the equalizing anchor. If the anchor or a portion thereof should break, the boxes on pins 9 will engage the nuts 11. Thus, a safety anchor is provided. Furthermore, if the 85 equalizing anchor breaks, the operation of lowering the drill pipe can be concluded by using the brake in the usual manner, the rods 8 serving to anchor the ends of the band in place.

What I claim is:—

1. In a draw works, the combination of a hoisting drum provided with a brake having two brake bands, means secured to the ends of the bands to adjustably pull and 90 tighten the latter, an equalizing anchor secured to a stationary support and to the other ends of said bands so as to take any pull upon the latter, and safety means connected to each brake band adjacent said anchor and to a stationary support, said means being normally loosely secured to said bands and arranged to engage and hold the latter upon their being released from said anchor.

2. In a draw works, the combination of 100 a hoisting drum, two brake drums arranged to rotate with said hoisting drum, two brake bands embracing said drums, means secured to the ends of said bands to adjustably pull and tighten the latter, safety rods slidingly 110

2
secured to the other ends of said brake bands whereby said bands may slide about said drums for a limited distance and be tightened thereon, a cross-bar pivotally secured between the last mentioned ends of said brake bands, an anchor bar pivotally secured to said cross-bar between the ends

thereof and to a stationary support so as to relieve said safety rods of normally supporting said brake band.

In witness that I claim the foregoing I have hereunto subscribed my name this 16th day of April, 1923.

AUTHER H. DAVIS.
